22 Claims. (Cl. 226—82.4)

2

in a horizontal path regardless of said first adjustment.

Still another object of the invention is the provision of change parts and adjustments which may be easily and rapidly installed or made so that the machine may accommodate cans of different heights and diameters without impairing the efficiency of the machine and so that the vacuum pump of the machine operates at substantially the same power efficiency regardless of the size can being closed.

Another object of the invention is the provision of an adjustment of the rotary valve which feeds the covers so that said valve and the external mechanism associated therewith may be moved upwardly and downwardly so that the covers are fed into the machine at a level spaced above the tops of the cans which is substantially constant regardless of the heights of the cans being closed.

Another object of the present invention is the use of two separate valves located remote from each other, one valve transferring open cans into the vacuum chamber and also transferring closed cans from the vacuum chamber and the other valve transferring covers in timed relationship into the vacuum chamber, both valves discharging their burdens into a common rotary turret where the cans and covers are positioned in vertical alignment with the covers spaced above the cans.

Still another object of the invention is the organization of the parts of the vacuum seamer in such manner that the path which the open top can travels from its entrance into the machine to the point at which the cover seats upon it is close to a straight line and the deviations from a straight line, necessitated because of the rotary movement of the turrets on which the cans are fed, are minimum and smoothly curved with the result that abrupt changes in direction of movement are avoided and hence the tendency of liquid contents of the cans to spill is largely eliminated. The substantially straight line movement of the cans is made possible in large measure through the location of the valve admitting covers remote from the valve admitting cans and thus avoiding the crowding of parts which would result from the use of a common entrance valve.

Further, the use of separate valves for cans and covers insures that the cans will be subjected to the vacuum existing in the vacuum chamber for an extended period of time before the covers are placed in contact therewith and hence assures that the air in the cans will be fully evacuated

1 This invention relates to a new and useful improvement in vacuum closing machines for open top cans. A principal object of the invention is to provide a vacuum closing machine into which open, filled cans and covers therefor may be fed through rotary valves so designed that prior to the time a cover has seated thereupon the cans move in a horizontal plane in a smoothly curved line having a minimum deflection from a straight line at a nearly constant speed with uniform acceleration and deceleration from such speed, thereby greatly reducing the tendency of the contents of the cans to spill as the result of abrupt changes in direction or velocity of movement.

Another principal object of the invention is the holding of the cans and the covers within their respective valves in such manner that the edges of the cans and covers do not wear grooves in the housings of the valves through which air may leak into the machine.

Another object of the invention is the provision of magnets within pockets of rotating turrets of the machine, said magnets attracting the cans and covers within the pockets and holding them against outward displacement from centrifugal force. Because of the magnets attracting the cans and covers into the rotating turrets for at least the last portion of their travel thereinto, no mechanical devices are required to move these components into said turrets and no portion of one rotating part intersects the path of travel of any other rotating part and consequently there is no danger of breakage of the parts of the machine by one part striking against another in the event that the timing of the machine should get out of order.

Another object of the invention is the provision of cam-actuated ejector levers within the pockets of the rotary can and cover valves to eject such components at the proper time and also to control movement of the cans into and from the can valve at uniform acceleration and deceleration, thereby reducing the tendency of the contents of the cans to spill.

A further object of the invention is the provision of adjustments of the clearances of the rotating and stationary parts of the can and cover valves to compensate for wear of the machine and also to compensate for variations in viscosity of the liquid contents of the cans which might have spilled and, upon being deposited between the can valve rotor and housing, cause binding between such relatively moveable parts, with additional adjustment so that the can moves

3

prior to commencement of the seaming operation.

It is a further object of the invention to restrict the amount of air which is admitted with the cans and covers and through the space between the valves and their housings and thus to economize on the amount of work and power required to create the desired degree of vacuum within the machine. The operation of the moving parts of the machine itself likewise requires a minimum of power, and this is another object of the invention. Further objects are the relatively low cost of manufacture, operation and repair of the machine, and the convenience with which the machine may be adjusted for variations in sizes of cans with consequent reduction in change-over costs.

The increasing use of vacuum packing, particularly of food products, by canners because of the resultant reduction in deterioration of the products during storage has led to the development of machines for seaming the covers to the cans while the cans are subjected to a vacuum. It is now common practice to use machines having conventional seaming mechanism enclosed in a vacuum chamber, but the problems which up until the present invention have not been successfully solved are to feed the cans and covers therefor into the machine so that the covers will be properly aligned on the cans prior to seaming yet the cans will be subjected to sub-atmospheric pressure for a sufficient period of time fully to evacuate the air in the cans and to move the cans through the machine so as not to cause spilling of the contents.

One common expedient is the use of a clinching machine outside the vacuum seamer which partially fixes the cover on the can. One disadvantage of this method is the necessity of using a separate clinching machine both from a standpoint of cost and of floor space occupied. Another disadvantage is the fact that the results obtained with such machines are poor and, further, non-uniform. If the amount of air in the can is small, the difference between its pressure and that of the vacuum chamber may be insufficient to raise the cover from contact with the can and hence the air may be incompletely evacuated. On the other hand, if there is a great difference in pressure between the contents of the can and the vacuum chamber, the force with which the cover is raised above the can may be so violent that the lip of the curled cover flange may seal with the underside of the can flange and hence the air will be incompletely evacuated. Or, the force may be so great as to blow the cover off the can entirely. All of these disadvantages of the use of a clincher are eliminated in the present invention.

Another expedient is the feeding of the cans and covers into the vacuum chamber through a common rotary valve, but this results in a crowding of the mechanism positioning the cover and can with respect to each other within the pockets of the rotor, which prevents travel of the open can in a substantially straight line and results in abrupt changes in the direction of travel of the can with consequent danger of spilling out of the contents, particularly if the contents or a part thereof consists of liquid. The crowding of the cover and can feed mechanisms adjacent the inlet valve also makes difficult access to the valve for inspection, adjustment or repair. In the present invention the covers are fed into the machine through a valve remote from the can valve and as a result the likelihood of

4

spilling is considerably reduced and accessibility to the inlet valves improved.

The various other expedients which have heretofore been adopted have other inherent disadvantages not present in the machine embodying the present invention and the advantages of the present invention, some of which are set forth in the preceding statement of the objects of the invention, are not present in such other machines.

With the above and other objects and advantages in view, the invention consists in the matters hereinafter set forth and more particularly pointed out in the appended claims, reference being had to the accompanying drawings, in which:

Fig. 1 is a schematic horizontal sectional view of the machine;

Fig. 2 is a vertical section through the can valve taken substantially along the line 2—2 of Fig. 1;

Fig. 8 is a section showing the can ejector lever and associated mechanism, taken along the line 8—8 of Fig. 1.

Fig. 9 is a perspective of a cover magnet used in the cover valve and in the feed turret.

General description of operation

By way of general description of the operation of the machine which embodies the present invention, it may be said that there is provided a vacuum chamber into which open cans 21 and covers 22 therefor are fed through separate turret valves, that within the chamber is a common turret onto which both the cans and covers are fed from their respective turret valves so that each can and its cover may assume vertical alignment, and that also within the chamber is a conventional seaming turret and associated seaming mechanism for double-seaming the cover to the can, to which seaming turret the cans and covers are transferred from the common turret. In its course through the machine prior to the time that the cover is placed thereupon, the open top can advances in a horizontal, level plane and the center of the can follows a smoothly curved path with an absolute minimum of deflection from a straight line, and the velocity of the can is as close to constant as is practicable, with accelerations and decelerations from said constant velocity being uniform. As a result of this movement of the can, the possibility of spilling the contents thereof is reduced far below that of conventional vacuum seamers. Another feature of the machine is the use of magnets in various pockets of the turrets to attract the cans and covers into the turrets and hold such components therein against centrifugal force.

Fig. 1 of the drawings is a schematic view showing the path of the cans and covers through the machine in dot-and-dash lines. The cans 21, which have preliminarily been filled and optionally pre-vacuumized, are fed into the machine along a suitable conveyor 23 in spaced and timed relationship. As each can passes the

5

trip lever 24 at point A it deflects the lever outwardly, the operation of the lever not affecting the progress of the can along the conveyor but setting in operation the feeding into the machine of a cover 22 which subsequently will be attached to the can. The description of the feeding of the cover will be deferred; however, it should be pointed out that a single cover is fed in to the machine for every can, that if no can enters the machine, no cover will be fed; and thus the possibility of a can not being covered or of a cover jamming the machine because there is no can on which it may seat is eliminated. At point B the can is transferred from the conveyor 23 to rotating feed star 26 and is directed into the can valve housing 21 in an arcuate path between inner feed rail 28 and outer feed rail 29. The rotating feed star 26 is fixed to shaft 31 and the shaft and star rotate, as viewed from above as in Fig. 1, in a clockwise direction. The shaft has a gear (not shown) affixed to its lower end, which gear is driven by a suitable electric motor through a gear train (not shown). It will be understood that all of the various rotating turrets and stars hereinafter described are also driven through said gear train, their direction of rotation, speed and spacing with respect to each other being controlled by proper selection and positioning of driving and driven gears and idlers. The direction of rotation of said rotating parts is shown by appropriate arrows in Fig. 1.

At point C the can is transferred into one of the several radially disposed pockets 32 in the can valve rotor 33 through an opening 34 in can valve housing 21. Through the instrumentality of a vacuum pump (not shown), a powerful vacuum is drawn within the housing 36 of the machine with which the can valve housing 21 communicates, so that once the pocket 32 communicates with housing 36, the can is subjected to a vacuum which evacuates the air in the can until its discharge from the machine through opening 34. One of the features of the present invention is the minimizing of the amount of work which must be done by the vacuum pump, which result is effected by reducing so far as possible the amount of air which enters the housing through the can and cover valves. The construction of the can valve rotor 33 involves a number of novel and important features, and, therefore, this member will be separately described hereinafter. The can is carried in the can valve rotor pocket 32 around to point D, whence it is forced out and directed by guide rails 38 and 40 into a pocket 39 of feed turret 41, the means for ejecting the can from the valve rotor also being described later in this specification. When the can 21 has moved around on the feed turret to point E, the cover 22 to be attached thereto has assumed vertical alignment with the can. In order to describe the operation which feeds the cover to point E, the description of the passage of the can through the machine will be interrupted.

When the can passed point A, its deflected the trip lever 24, which movement was transmitted by rod 42 to mechanism to feed a single cover from the vertical stack of covers 43 disposed between four vertical posts 44. There are a number of well-known mechanisms to cause the covers to move downward from the stack one at a time, and since this particular feature is not one of the parts of the present invention, such mechanism will not be described in detail, its construction being understood by those skilled in

6

the art. Having been fed vertically downward, the cover is moved to point G from point F by the reciprocating transfer finger 46. Said finger reciprocates in an arcuate path about its shaft 47 as a pivot, and it should be understood that the reciprocation of the finger is continuous and in closely timed relationship with respect to the various rotating parts of the machine and that its actuation is not dependent upon deflection of trip lever 24. Point G is an optional station, but as shown in Fig. 1, the cover momentarily comes to rest at such point and a suitable marker 48 may stamp or emboss the cover with a code symbol so that the contents of the can may be identified after packing. The construction and operation of such markers is also well known in the art and hence not described herein. After sufficient time has elapsed for the marking operation, the cover is picked up by one of the arms 49 of rotating star 51 and moved into one of the pockets 52 of the cover feed valve rotor 53 at point H, through opening 54 in the cover valve housing 56 which also communicates with main housing 36. The cover is retained in position during its travel from point F to point H by cover guide rails 57 and 58.

The cover is carried around in the valve rotor 53 from point H to point I and thence ejected, and because the construction of said valve rotor involves novel and important features, a detailed description thereof is deferred. At point I, the cover is transferred into a pocket 39 in feed turret 41, said pocket being the same pocket into which the corresponding can to which the cover will be attached is subsequently transferred at point D. Guide rails 59 and 61 assist in maintaining the cover in proper horizontal position. The construction of the guide rails 59 and 61 and feed turret 41 is also subsequently described in detail.

At point E the can 21 and its cover 22 are in axial alignment, although, as will appear, the cover is elevated above the can. The can and its cover travel in such alignment to point J at which point their path of travel intersects the circular path of the conventional seaming chucks 62 and lifter chucks (not shown) of seaming turret 63 and the can and cover are transferred to said seaming turret, being guided thereto by guide rails 64 and 59-61. The construction and operation of such seaming chucks and lifters and also seaming rolls 66 associated therewith are conventional and well known in this art. It will be sufficient to state that the lifter chucks raise the can until at point J the cover seats on the can and at point K the two components are clamped together between the lifter and seaming chucks and rotated thereby. The well-known preliminary seaming operation is performed by one of seaming rolls 66 between points K and L and between points L and M the final seaming operation is performed by another seaming roll 66. At point N the lifter chuck begins to lower the can until point O is reached, when the discharge turret 61 diverts the closed can 88 from the seaming turret 63 and the can, guided meanwhile by rails 40 and 71, is carried to point P and fed into a pocket 32 of can valve rotor 33. The rotor carries the can around to point Q whence it is discharged through opening 34 in housing 21 and picked up by discharge star 72 and carried around to point R, at which point it may be transferred to any suitable conveyor.

To provide for inspection and repair and also to facilitate the installation of various "change

parts" used to adapt the machine to cans of various heights and diameters, the housing 36 is provided with a plurality of doors (not shown) suitably positioned to afford access to the interior of the machine. Can valve housing 27 and cover valve housing 56 may also be opened to provide access to the interior of the housing and are sealed closed by means of latches 73 to make the housing substantially air-tight.

Also, in order to accommodate cans of varying heights, the entire sub-assembly consisting of the cover feed stack 43, marker 48 and cover feed valve 53 together with their associated housing 56 and driving mechanism is made vertically adjustable. As seen in Fig. 7, a screw 74 is fixed to housing 56 and is provided with a nut 76 which bears against a pillow block 75 fixed to the main portion of the machine. By rotating nut 76 the sub-assembly may be raised and lowered so that the covers will be fed into the machine at the proper level for the height of can being closed.

The foregoing description has been confined to a vacuum seamer. The same structure may be used if the packing is done at greater than atmospheric pressure, and, of course, the machine could, if desired, be operated at atmospheric pressure.

Can valve

The construction of the rotary can valve is shown in Figs. 1 and 2 and partially in Fig. 8. The purpose of the valve is to feed cans 21 into the vacuum chamber with the admission of as little accompanying air as possible and in such a smooth and controlled manner as to reduce the spilling of the contents of the can to a minimum. The valve serves a further function of feeding closed cans 68 out of the vacuum chamber.

The can valve rotor 33 is provided with a plurality of radially disposed pockets 32, six pockets as shown in Fig. 1, into which cans may be positioned. The rotor is mounted on a gear-driven, vertically-disposed shaft 81 for rotation therewith and its outer peripheral surface 82 revolves within the inner surface 83 of housing 27 with a running clearance of 0.003 to 0.005 inch. An oil film is deposited by an automatic lubricator (not shown) between the two surfaces for lubrication and also to effect an air-tight seal therebetween. Although, as has been stated, one of the objects of this invention is to reduce the spillage of the contents of the can, in practice in operations preceding the seaming of the cover some spillage occurs and the liquid collects on the exterior of the can, and such liquid tends through centrifugal force to collect on the inner surface 83 of housing 27. The liquids deposited in cans during the filling operation are of various types, such as sugar solutions of various concentrations, and the viscosity of such liquids varies and evaporation of the water content may make them quite sticky. In order to eliminate the tendency of the rotor 33 to bind in the housing 27 as a result of deposit of viscous liquids between the rotating members, provision is made for adjustment of the clearance between such members, and such adjustment also may be made to accommodate gradual wearing of the parts after prolonged use of the machine. In order to provide for the aforementioned adjustment of clearance, both the outer surface 82 of the rotor and the inner surface 83 of the housing are machined at a taper so that the surfaces are in fact frusto-conical, and the rotor is vertically adjustable on its shaft 81, whereby the clearance may be varied by raising or lowering the position of the

rotor with respect to the housing. The shaft is supported for rotation in the housing by bearings 84 and 86 at the top and bottom, respectively, and the upper end of the shaft is threaded and provided with a nut 87 and lock nut 88. The nut 87 is tightened or loosened against the inner race of bearing 84 and hence shaft 81 and rotor 33, keyed and pinned thereto, may be raised or lowered. In order to insure that the path of the can into and from the pockets of the rotor is smooth, the bottom wall 89 of each pocket, on which the can rests during its passage through the valve, is provided with shims 91, the number and thickness of which may be adjusted to compensate for the raising and lowering of the rotor.

One of the principal features of the valve rotor is the use of a permanent magnet 92 in each pocket to draw the can toward the center of the rotor, thus performing two functions: First, the magnet completes the drawing of the can into the valve and therefore, the fingers 93 of star 26 need never extend inside housing 27 and hence there is no chance of the fingers contacting rotor 33 in the event that the timing of the rotor and star should accidentally come out of adjustment; otherwise serious damage to the machine might result. Second, the magnet overcomes the centrifugal force operating on the can and holds the can in its proper position in the pocket instead of allowing the bead 94 of the bottom seam of the can to wear against the inner surface of the housing; thus the tendency which exists in other machines for the bead to wear a groove in the housing is overcome and the consequent leakage of air through such groove is eliminated.

The permanent magnets 92 in each pocket are U-shaped with the extending legs pointed radially outwardly and disposed one above the other. The magnet is held on the rotor by non-magnetic screws 96 and a spacer 97 of brass or other non-magnetic material is interposed between the base of the magnet and the rotor. The magnet is strong enough in intensity to pull the filled can into the pocket of rotor 33 and to hold the can in innermost position against centrifugal force.

Each pocket of the rotor is fitted with change parts which may be changed for cans of different heights and diameters. So that the magnet may attract the can into the pocket without tendency of the contents of the can to spill, the magnet itself may be changed to accommodate cans of different heights by using magnets having different distances between the horizontally disposed legs so that the lower leg will be about the same distance above the bottom of the can as the top leg is below the top of the can. Further, so as to accommodate cans of different diameters, the spacer 97 may be changed so that the can is drawn into the pocket just far enough so that the lower bead 94 of the can clears the inner surface 83 of the housing 27 without rubbing thereagainst.

So as to economize on power, it is desirable that as little air be drawn into the machine with the can as possible, yet the pockets 32 must be made high enough to accommodate tall as well as short cans. In order to displace the air which would otherwise be drawn in with a short can, spacer 98 is fastened to the top wall 99 of pocket 32 to take up most of the space between the top of the can and the top wall of the pocket, such spacer being changeable for various heights of cans. Below spacer 98 is hold-down plate 101 fastened thereto, which just clears the top of the can and thereby overcomes any tendency of the contents

of the can to blow out of the can when it is subjected to vacuum. Between hold-down plate 101 and spacer 98 are shims 102 performing the reverse function of shims 91, so that as the thickness of shims 91 is increased the thickness of shims 102 is decreased and vice versa. A recess 103 in the spacer 98 receives the edge of a cover adjacent point D so as to allow for clearance of the parts.

From the foregoing it will be seen that there are adjustments provided in each of the pockets of the rotor for the following varying conditions:

(1) Variations in viscosity of the liquid content of the cans and wear of the parts—i. e. vertical adjustment of the rotor 33 with respect to the housing 27 and compensating adjustment of shims 91 and 102.

(2) Variations in can diameters—i. e. change of thickness of spacers 97.

(3) Variations in can heights—i. e. change of spacers 98 and magnets 92.

In order to eject cans from the pockets 32 at points D and Q, each pocket is provided with a cam-actuated ejector lever 104, which lever also performs other functions herein described. Lever 104 is substantially crescent shaped and bored at one end, through which bore passes a vertically disposed shaft 106 to which the lever is fixed for rotation therewith. The other end 107 of lever 104 engages the can. Shaft 106 passes through the top wall 99 and is journaled in bottom wall 89 of pocket 32 with bushings 108 interposed between the shaft and the walls so that the shaft may rotate freely. An interiorally projecting horizontal arm 109 also provided with a bushing 111 embracing shaft 106 is disposed approximately midway of the pocket 32 and steadies the shaft and also prevents upward movement of lever 104. To the upper end of shaft 106 is fixed horizontally disposed arm 112 to the opposite end of which is mounted cam follower roller 113. The roller is guided in cam groove 114 in the lower surface of horizontally disposed cam plate 116, which plate is carried in the housing 27. Plate 116 has a vertically projecting adjustment ear 117 engaged by opposed adjustment screws 118 which project outside housing 27 so that by tightening one screw and loosening the other a slight movement of cam plate 116 about shaft 81 may be made for adjustment of the timing of the cam. (See Fig. 8.) It is apparent that by proper design of the groove 114, the end 107 of lever 104 may be caused to move outwardly and inwardly of pocket 32.

The design of cam groove 114 is such that lever end 107 at point C is slightly behind the can 21 as it is moved into the pocket by fingers 93 of star 26 and by the force of attraction of magnet 92. Thus in the event that the machine should stop suddenly, the finger end 107 will prevent the can from jarring or tipping. As the can moves into the pocket it is contacted by end 107 and the lever retards movement of the can so that when the can finally abuts magnet 92 it is moving gradually inward with uniformly decelerated speed instead of coming against the magnet abruptly; this feature also prevents spilling of the contents of the can. In such fully retracted position, the lever end 107 is disposed within the horizontally radially disposed legs of magnet 92, as shown in the right half of Fig. 2. The lever end 107 then moves outwardly to discharge the can at point D against the force of attraction of the magnet and the lever end then retracts so as to admit closed cans 68 at point 75

P and then projects again so as to discharge the closed cans at point Q. With the foregoing functions in mind, it is thus a simple matter to properly design cam groove 114 so that with the cam plate 116 stationary in the housing 27 rotation of rotor 33 and shaft 106, arm 112 and roller 113 will cause inward and outward movement of lever end 107 to accomplish the desired result. Thus the open top can may be caused to enter and leave the pocket with a smooth, evenly accelerated and decelerated motion and thereby the tendency of spilling the contents of the can is largely overcome.

Cover valve

The cover 22 for the can is fed into the machine through a separate rotary cover valve located remote from the can valve, although both the can valve and the cover valve discharge their burdens into a common feed turret 41. The cover valve is in some respects quite similar in construction and operation to the can valve, but inasmuch as the problem of spilling the contents of open top cans is not present, and since the height of all covers is about the same whereas the height of cans varies considerably, the construction of the cover valve is simpler than the can valve.

This valve, illustrated particularly in Figs. 1 and 3, contains a rotor 53 having a plurality of pockets 52 into which the covers are fed at point H. The rotor is mounted on a gear-driven vertically disposed shaft 119 for rotation therewith and its outer peripheral surface 121 is tapered to fit a corresponding taper in the opposed inner surface 122 of cover valve housing 56. Shaft 119 is mounted in the housing by means of bearings 123 and 124 and the upper end of the shaft is threaded and provided with nuts 126 which may be tightened and loosened against the inner race of bearing 123 to provide for vertical adjustment of rotor 53 with respect to housing 56 so as to take up wear of the parts with passage of time. An oil film is deposited by an automatic lubricator (not shown) for purpose of lubrication and also to seal the space between the surfaces against the admission of air. In all these respects the cover valve resembles the can valve.

The cover valve also is provided with magnets 127 (see Fig. 9), there being two small magnets disposed at the inmost position of each pocket 52, said magnets attracting the cover into the valve at point H off the fingers 49 of rotor 51 and holding it in the pocket 52. Thus the fingers 49 of star 51 at no time need enter within housing 56 and consequently in the event of mis-timing there is no danger of star 51 and rotor 53 hitting each other, with resulting serious damage to the machine. Magnets 127 also prevent the edge of the cover from wearing a groove in the inner surface 122 of the housing through which air may leak into the vacuum chamber, although the weight of such covers being so much less than that of filled cans, this feature is not so important as in the case of magnets 92 of can valve rotor 33. The magnets are mounted in non-magnetic inserts 128, which are, in turn, mounted within each pocket 52.

Each pocket is also provided with a cam-actuated ejector lever 129 which forces the cover out of the valve at point I. Said lever is fixed at one end to vertical shaft 131, its other end 132 being free to engage the cover 22 and move same. Shaft 131 is journaled in rotor 53 and carries a lever 133 at its opposite end and said lever also

11

carries a cam-engaging roller 134. The roller is confined for movement within a groove cam 136 cut in the lower face of cam plate 137 adjustably fixed to housing 56. The cam plate has an up-standing ear 138 attached thereto and the opposite flat surfaces of said ear are engaged by opposed screws 139 which extend exteriorally of the housing so that by tightening one screw and loosening the other the plate may be given a slight rotary movement about shaft 119 as a center and the timing of the cam may be adjusted. It is readily apparent that the movement of roller 134 in groove 136 is transmitted through lever 133 and shaft 131 so as to cause the end 132 of lever 129 to move inwardly and outwardly in pocket 52. The timing of the cam is such that the ejector lever is retracted as the pocket passes point H and projected at point I to discharge the cover into the feed turret.

Feed turret and cover guide rails

The feed turret 41 receives covers 22 at point I and open top cans 21 at point D and carries them around to point J where they are discharged into the seaming turret 63. Covers are held within the radially disposed pockets 39 of the turret by magnets 141 (see Fig. 9), but to insure against displacement of the covers prior to arrival at point J, arcuate guide rails 59 and 61 are provided as a safety factor to preserve the horizontal positioning of the covers so that the covers may float between said rails.

The feed turret, fixed to shaft 143, shown in Figs. 1 and 4, has a plurality of radially disposed pockets 142 into which the cans and covers fit and the turret constitutes one of the change parts of the machine since it may be interchanged to accommodate cans of different diameters and heights. It should be mentioned, as has been previously stated, that the cover feed valve rotor 53, together with marker 48 and housing 56 is vertically adjustable so that the covers will always be fed into the machine at the proper height to fit into the feed turret regardless of the height of the cans to which they are to be attached.

The feed turret 41 consists essentially of two parts, one part consisting of two horizontally disposed flanges 144 and 146 pocketed to receive can bodies and the other part, positioned above the first part being pocketed to receive the covers for the cans. The cover part carries two magnets 141 for each pocket designed to engage and hold inwardly the edge of the cover against centrifugal force occasioned by rotation of the turret, the covers resting on a horizontal, pocketed ledge 145 of turret 41. Thus rotation of the feed turret carries the cover and can around to point J.

The magnets 141 tend to hold the covers horizontal, but to insure such positioning of the covers, a pair of arcuate horizontally disposed guide rails 59 and 61 spaced vertically one above the other are positioned to surround a portion of the feed turret and the portion of the edge of the cover opposite that portion of the edge which is held within the turret by magnets 141 moves within the space between said rails, as shown in Fig. 4. The guide rails 59 and 61 are spaced one above the other by guide spacers 147 and 148. It will be noted that guide rails 59 and 61 are cut away at 149 as shown particularly in Fig. 5 so as to clear the rotor 33 of the can valve adjacent point D. It will also be noted that the guide rails are cut away at 151 so as to clear the can and cover as they are moved upward by the ascending lifter chuck to engage the seaming chuck 62 at point J.

12

By reason of this cutting away of the guide rails at 149, the guide rails alone cannot be relied upon to preserve the horizontal position of the covers. Therefore magnets 141 are the principal factors in holding the covers horizontal and the guide rails are auxiliary thereto.

What is claimed is:

1. A rotatable turret for a can seaming machine having a plurality of pockets shaped to receive at least a portion of one of the components of a sealed can, said components including an open can and a cover therefor, and a magnet disposed within a pocket to draw one of said components into said pocket and hold said component against displacement by centrifugal force.
2. A rotatable valve turret for a can seaming machine having a plurality of pockets shaped to receive at least a portion of one of the components of a sealed can, said components including an open can and a cover therefor, a magnet disposed within a pocket to draw one of said components into said pocket and hold said component against displacement by centrifugal force, an ejector lever movable in said pocket to eject said component against the force of attraction of said magnet, and means to actuate said ejector lever.
3. A rotatable valve turret for a can seaming machine having a plurality of pockets shaped to receive at least a portion of one of the components of a sealed can, said components including an open can and a cover therefor, a magnet disposed within a pocket to draw one of said components into said pocket and hold said component against displacement by centrifugal force, an ejector lever moveable in said pocket to eject said component against the force of attraction of said magnet, and cam means actuated by rotation of said turret to move said ejector lever.
4. A can valve for conveying cans from one zone to another zone of different pressure comprising, a housing having at least two openings therein, a rotor rotatable within said housing and having a plurality of can-receiving pockets therein, and a can attracting magnet within one of said pockets.
5. A can valve for conveying cans from one zone to another zone of different pressure comprising, a housing having at least two openings therein, a rotor rotatable within said housing and having a plurality of can-receiving pockets therein, a can-attracting magnet within one of said pockets, and a magnet spacer between said magnet and said rotor.
6. A can valve for conveying cans from one zone to another zone of different pressure comprising, a housing having at least two openings therein, a rotor rotatable within said housing and having a plurality of can receiving pockets therein, a can-attracting magnet within one of said pockets, and a spacer vertically positioned from said magnet.
7. A can valve for conveying cans from one zone to another zone of different pressure comprising, a housing having at least two openings therein, a rotor rotatable within said housing and having a plurality of can receiving pockets therein, a can attracting magnet within one of said pockets, and an ejector lever movable within said pocket.
8. A can valve for conveying cans from one zone to another zone of different pressure comprising, a housing having at least two openings therein, a rotor rotatable within said housing and having a plurality of can-receiving pockets therein, a can attracting magnet within one of

13

said pockets, an ejector lever movable within said pocket, first cam means connected to said ejector lever and second cam means adjustably positioned in said housing engageable with said first cam means.

9. A can valve for conveying cans from one zone to another zone of different pressure comprising, a housing having at least two openings therein, a rotor rotatable within said housing and having a plurality of can-receiving pockets therein, a can attracting magnet within one of said pockets, an ejector lever movable within said pocket, first cam means connected to said ejector lever and second cam means adjustably positioned on said housing engageable with said first cam means, said ejector lever controlling admission of said cans into said pocket at uniformly decelerated speed and ejection of said cans from said pocket at uniformly accelerated speed.

10. A valve for conveying from one zone to another zone of different pressure components of a sealed can, said components including an open can and a cover therefor, comprising, a housing having at least two openings therein, a rotor rotatable within said housing and having a plurality of pockets to receive said components, and a magnet within one of said pockets arranged to draw a component into said pocket.

11. A valve for conveying from one zone to another zone of different pressure components of a sealed can, said components including an open can and cover therefor, comprising, a housing having at least two openings therein, a rotor rotatable within said housing and having a plurality of pockets to receive said components, a magnet within one of said pockets arranged to draw a component into said pocket, and an ejector lever movable within said pocket.

12. A valve for conveying from one zone to another zone of different pressure components of a sealed can, said components including an open can and a cover therefor, comprising, a housing having at least two openings therein, a rotor rotatable within said housing and having a plurality of pockets to receive said components, a magnet within one of said pockets arranged to draw a component into said pocket, an ejector lever movable within said pocket, first cam means connected to said ejector lever and second cam means on said housing engageable with said first cam means.

13. A can cover valve for conveying covers from one zone to another zone of different pressure, comprising, a housing having at least two openings therein, a rotor rotatable within said housing and having a plurality of pockets to receive said covers, a magnet within one of said pockets arranged to draw a cover into said pocket, a cover ejector lever in said pocket, first cam means connected to said ejector lever, and second cam means on said housing engageable with said first cam means.

14. A can and cover feed turret having a plurality of can receiving pockets and corresponding cover receiving pockets for each said can receiving pocket spaced thereabove and a magnet in said cover receiving pocket arranged to draw a cover into said pocket.

15. In combination, a can and cover feed turret having a plurality of can receiving pockets and corresponding cover receiving pockets spaced thereabove and a magnet in one of said cover receiving pockets arranged to draw a cover into said pocket, and an arcuate cover guide rail

14

surrounding a portion of said turret at the level of said can receiving pockets.

16. In combination, a can and cover feed turret having a plurality of can receiving pockets and corresponding cover receiving pockets spaced thereabove and a magnet in one of said cover receiving pockets arranged to draw a cover into said pocket, and arcuate guide rails spaced one above the other surrounding a portion of said turret at the level of said can receiving pockets.

17. In an open top can seamer, a first turret, a second turret, a third turret, said second turret being offset laterally with respect to a line joining said first and third turrets, a fourth turret located adjacent said second turret and remote from said first turret, and a plurality of pockets in said turrets, whereby cans may be transferred in said pockets of said second turret from said first turret to said third turret with smoothly curved, slight deviations from a straight line and covers for cans may be transferred from said fourth turret to said third turret in said pockets of said second turret.

18. In a vacuum seamer, a housing, a can valve rotor rotatable partly within and partly without said housing, a seaming turret rotatable within said housing, a feed turret rotatable within said housing, a cover valve rotor rotatable partly within and partly without said housing, a plurality of pockets in each of said turrets and said rotors, and means to rotate said feed turret in a direction opposite to the direction of rotation of said seaming turret and said rotors in timed relation thereto, whereby cans may be transferred in pockets of said feed turret from said can valve rotor to said seaming turret with smoothly curved, slight deviations from a straight line and covers for cans may be transferred from said cover valve turret to said seaming turret in said pockets of said feed turret and positioned above a corresponding can.

19. A vacuum seamer as claimed in claim 18 having a magnet in each of said pockets of said can valve rotor, cover valve rotor and feed turret.

20. A vacuum seamer as claimed in claim 18 having a magnet in each of said pockets of said can valve rotor, cover valve rotor and feed turret and a cam-actuated ejector lever in each of said pockets of said can valve rotor and said cover valve rotor.

21. In a vacuum seamer, a first rotary turret valve for transferring open top cans into said seamer and a second rotary turret valve transferring covers for said cans into said seamer, said second valve being positioned remote from said first valve.

22. In a vacuum seamer, a first rotary turret valve for transferring open top cans into said seamer and closed cans out of said seamer and a second rotary turret valve for transferring covers for said cans into said seamer, said second valve being positioned remote from said first valve.
